UNITED STATES PATENT OFFICE.

JOHN W. SCOTT, OF NEW YORK, N. Y., ASSIGNOR TO STANDARD SAFETY TREAD CORPORATION, OF NEW YORK, N. Y., A CORPORATION OF NEW YORK.

NONSLIP TREAD.

Application filed August 19, 1927. Serial No. 214,020.

This invention is an improvement in treads for stairways and the like, and more particularly in a nonslip tread.

In treads as heretofore constructed, means in the form of a molded metal reinforcement is provided for the edge of the stair tread, and for a part of the top thereof adjacent to the edge.

The usual floor covering is placed on that portion of the reinforcement on the upper face of the tread, a rib, undercut or otherwise, being usually provided at or near the extreme edge of the tread against which the usual floor covering, such as cork or linoleum 15 is abutted.

Thus the floor covering lies upon the reinforcement, and in use, the covering becomes broken or creased at the edge of the reinforcement, so that there is a visible marring 20 of the covering along this line.

This is true even when the reinforcement is gradually thinned to a feather edge, as there is always more or less displacement of the floor covering upward by the reinforcement.

Any metal left exposed to wear by persons using the stair quickly becomes smooth and slippery, so that an insufficient hold is offered for the foot, and there is a liability to 30 falls from slipping on the reinforcement with consequent injury.

One of the primary objects of the present invention is the provision of a construction of tread wherein a minimum of metal is exposed to wear, while at the same time the edge of the stair tread is sufficiently reinforced, and wherein the reinforcement and usual floor covering abut squarely, instead of lapping one upon the other.

40 A further object is the provision of a tread carrying an exposed layer of an abrasive substance, having a high coefficient of friction, such for instance as powdered carborundum.

45 A further object is the provision of mechanism in connection with the tread for firmly anchoring the abrasive material to the tread, against the possibility of displacement by chipping and the like.

50 A further object is to provide mechanism in connection with the anchoring means for the abrasive, to connect the tread to the stair tread, in such manner that while firmly held, it is capable of removal when desired for any purpose.

With these and other objects in view the invention consists in the construction and novel combination of parts fully described hereinafter, illustrated in the accompanying drawings, and pointed out in the claims 60 appended hereto, it being understood that various changes in the form, proportion, size and minor details of construction within the scope of the claims, may be resorted to without departing from the spirit of the 65 invention.

In the drawings forming a part hereof:—

Fig. 1 is a perspective view of a part of a stair provided with the improved tread.

Fig. 2 is a transverse section showing one 70 of the anchoring means.

In the present embodiment of the invention, the improved tread is shown in connection with the tread 1 of a stair, usually of wood or like material, having the free edge 75 thereof which extends beyond the riser rounded as shown.

The tread comprises a body portion 3 having an undercut channel 4 in its upper face, extending the full length of the tread, 80 and substantially the full width thereof. The tread is also provided with a depending flange 5, fitting the rounded edge 2 of the stair tread and covering the same.

The front wall 6 of the channel is a continuation of the flange 5 as shown, and the rear wall 7 has its outer face perpendicular to the stair tread when the tread is in place, so that the usual floor covering indicated at 8, such as linoleum or the like, may be 90 abutted squarely against the said wall, thus to provide a close joint between the floor covering and the reinforcing tread.

The channel 4 is filled with an abrasive 9, such as powdered carborundum or the like, 95 molded into shape in the channel, and held in part by the undercut faces of the front and rear walls 6 and 7 of the channel. In addition the body of the tread is provided at suitable intervals with openings 10, which as shown are reamed or undercut, flaring from the channel. The said openings are designed to receive locking projections on the abrasive, thus to more firmly anchor the abrasive in the channel.

100 The tread is adapted to be connected to the stair tread, by means of screws 11, or the like, which are passed through openings in the body of the tread. In each of these openings is arranged a sleeve or fun- 110

nel shaped eyelet 12. That is each eyelet consists of a substantially cylindrical portion passing through the opening, and upset on the underside of the tread body, and 5 a flaring or funnel shaped portion which extends above the upper face of the body, and has the free end thereof substantially flush with the tops of the walls 6 and 7.

The eyelets are intermediate the side walls, 10 and may be spaced at suitable intervals. The screws are passed through the eyelets, the funnel shaped or flaring upper end being shaped to fit the head of the screw as shown. Thus in addition to providing a 15 housing for the screw, the eyelets serve to anchor the nonslip filling. The filling also acts to hold the eyelets in place.

The improved tread provides a neat finish for the upper face of the stair tread, 20 with a minimum exposure of metal, and with a strip of material, resistant to wear, and with a high coefficient of friction. This strip is at the edge of the stair tread, in the position most subject to wear. It is firmly 25 anchored to the reinforcing tread, and the entire device may be easily removed when desired for any purpose.

What is claimed as new is:—

1. A nonslip tread of metal including a 30 body adapted to lie on the upper face of the stair tread, and a depending flange shaped to fit the edge of the tread, the upper face of the body having a channel extending the full length and substantially the full 35 width thereof, for receiving abrasive material with a high coefficient of friction, and means for anchoring the abrasive in the channel, including undercut side walls, the body having openings extending through the 40 same in the bottom of the channel for receiving the abrasive material.

2. A nonslip tread of metal including a body adapted to lie on the upper face of the 45 stair tread, and a depending flange shaped to fit the edge of the tread, the upper face of the body having a channel extending the full length and substantially the full width thereof, for receiving abrasive material with a high coefficient of friction, and means for 50 anchoring the abrasive in the channel, including undercut side walls, and undercut openings in the body, said openings extend-

ing through the body in the bottom of the channel.

3. A nonslip tread of metal including a 55 body adapted to lie on the upper face of the stair tread, and a depending flange shaped to fit the edge of the tread, the upper face of the body having a channel extending the full length and substantially the 60 full width thereof, for receiving abrasive material with a high coefficient of friction, and means for anchoring the abrasive in the channel, including undercut side walls, and openings having eyelets held therein, the 65 upper ends of the eyelets flaring, said eyelets adapted to receive a securing means for connecting the tread to a stair tread.

4. An attachment for stair treads having a body adapted to lie on the upper face of 70 the stair tread, and a flange to fit the front edge thereof, the body having a channel extending longitudinally thereof, and provided with substantially funnel shaped eyelets at suitable intervals in the channel to enable 75 the passage of securing means for the tread, and a filling of nonslip material in the channel and about the eyelets.

5. An attachment for stair treads having a body adapted to lie on the upper face of 80 the stair tread, and a flange to fit the front edge thereof, the body having a channel extending longitudinally thereof, and provided with substantially funnel shaped eyelets at suitable intervals in the channel to enable 85 the passage of securing means for the tread, the channel adapted to receive a filling of nonslip material to be anchored by the eyelets.

6. An attachment for stair treads having 90 a body adapted to lie on the upper face of the stair tread at the front edge thereof, and a flange to fit said edge, the body having an undercut channel extending the full length thereof and substantially the full width, and 95 provided with openings in the bottom of the channel extending through the body, sundry of the openings flaring toward the bottom of the body and funnel-shaped eyelets in the other openings for the purpose specified.

Signed at New York in the county of New York and State of New York this 15th day of August A. D. 1927.

JOHN W. SCOTT.
